(Model.)

S. D. WARFIELD.

GREEN CORN CUTTER.

No. 247,718.

Patented Sept. 27, 1881.

UNITED STATES PATENT OFFICE.

SOLOMAN D. WARFIELD, OF BALTIMORE, MARYLAND.

GREEN-CORN CUTTER.

SPECIFICATION forming part of Letters Patent No. 247,718, dated September 27, 1881.

Application filed August 10, 1881. (No model.)

To all whom it may concern:

Be it known that I, SOLOMAN D. WARFIELD, of the city of Baltimore and State of Maryland, have invented certain Improvements in Green-Corn Cutters, of which the following is a specification.

This invention relates to a machine in which an ear of corn supported axially between centers is stripped of the adhering grain by means 10 of a longitudinally-moving knife in a series of cuts, the ear being partially revolved after each operative movement of the knife.

It further relates to means whereby a cut of uniform depth is obtained, and to other details 15 of construction of the machine, as will herein-after appear.

In the further description of my said invention which follows reference is made to the accompanying drawings, forming a part hereof, and in which—

Figure I is a side view of the machine. Fig. II is a plan of the same. Figs. III and IV are views of certain parts of the machine on an enlarged scale. Fig. V illustrates a modification 25 in the construction of a part of the machine.

Similar letters of reference indicate similar parts in all the views.

A is the bed-plate of the machine. B is a 30 revoluble shaft, supported in a suitable frame, C, having a pointed blade or driving-center at its inner end, which is inserted in one end of the ear of corn from which the grain is to be removed. The other end of the ear of corn is 35 supported by a bar, D, having a stationary center, and a series of prongs adapted to be revolved independently of the center, which are forced into the ear. The bar D is adapted to slide longitudinally in the stand a, and it is 40 notched at its upper edge to engage with a pawl, b, pivoted to one part of the stand. A spring, E, serves to keep the bar D, when not held by the pawl b, at its greatest distance from the rotary driving center or blade of the 45 shaft B.

The ear of corn is first pressed on the driving blade or center, and the bar D is then moved forward until the stationary center and the revoluble prongs enter the other end of 50 the ear. As the bar D is advanced it is held and its retraction prevented by means of the pawl b.

F is a knife, secured rigidly to a carrier, G, which is pivoted to a holder, H. The holder H is supported on guide-rods I, and it has a 55 reciprocating motion, being attached to a crank, K, as shown in the drawings.

The construction of the knife, carrier, and holder will be understood by reference to Fig. III. A roller, d, is adjustably attached to the 60 knife-carrier G, and rests on the ear in advance of the knife, to give a uniform depth of cut without reference to any longitudinal curvature or irregularity in shape of the ear.

By reference to Fig. III it will be seen that 65 vertical adjustment of the roller is effected by means of a screw, e. The knife is retained in contact with the ear by means of a spring, f.

L are miter-gears, connecting the shaft B with the counter-shaft M, on the outer end 70 of which counter-shaft is secured a ratchet-wheel, N.

O is a spring-pawl, projecting from the knife-holder H, which, at each backward movement of the said holder and its attachments, comes 75 in contact with the teeth of the ratchet-wheel N and effects a partial revolution of the ear. By this means, if the gearing and ratchet-wheel are arranged with reference to the spring-pawl to effect a fifth of a complete revolution 80 of the ear at each revolution of the crank K, the grain will be stripped in five cuts, as will be readily understood.

P is a guide-bar, upon which an extension, g, of the knife F rides as the said knife passes 85 beyond the end of the ear in its backward movement, thus preventing its contact with the shaft B or the frame C. A similar guide-rod, R, is fastened to the bar D, and it acts in substantially the same manner as the one P, 90 only that it comes into contact with the knife-carrier, instead of with an extension of the knife in the forward stroke.

When an ear of corn has been stripped of its grain, and the cob only is left between the 95 centers, the operator forces the pawl B from contact with bar D, when the spring E assumes its original position, drawing the said bar back. The force exerted in this retractive movement of the bar D is used to disengage 100 the cob from the center in the following manner: A small rod, h, having an eye at one end, which encircles the driving-center or blade, is confined within bearings i, and adapted to have

a longitudinal movement therein. The other end of said bar is bent upward and to such position as to come in contact with a brace, *k*, on the guide-rod *R* when the same springs back.

5 When the ear of corn is placed between the centers the rod *h* is forced back or to the position shown in Figs. I and II of the drawings; but upon the release of bar *D* it is moved in a contrary direction by the brace *k* coming into contact with its upturned end, and the eye of the rod *k* is thus forced against the end of the corn-cob and detaches the same from the driving-center.

In Fig. V the knife *F* is shown with a central pointed point and two angular cutting edges; but its operation is substantially the same as that of the knife shown in the other figures.

Where it is designed to use the machine for removing cooked corn from the cob for table use, I propose to apply a blade to the roller or to the knife to sever the outer casing of the grain, and in such case a scraper could be used to remove those parts of the grain not detached by the knife.

If desired, the crank and connecting-rod for operating the knife may be dispensed with, and the knife moved longitudinally of the ear by means of a handle, which is shown in dotted lines in Fig. II and represented by *V*.

30 I claim as my invention—

1. In a green-corn cutter, a pair of centering-points adapted to support axially an ear of corn, and means for effecting an intermittent partial rotation of the ear, combined with a longitudinally-moving knife, and a roller to govern the depth of cut of the said knife, substantially as specified.

2. In a green-corn cutter, a pair of centering-points adapted to support axially an ear of corn, and means for effecting an intermittent 40 partial rotation of the ear, combined with a longitudinally-moving knife, a gaging-roller, and guides to sustain the said knife when the same passes beyond the ear, substantially as specified.

3. In a green-corn cutter, a revoluble shaft with a pointed blade or driving-center adapted to sustain one end of an ear of corn, combined with a bar constructed to support the other end of the said ear, the said bar having a reTRACTING-SPRING, and a toothed surface to engage with a pawl, substantially as and for the purpose specified.

4. In a green-corn cutter, a pair of centering-points adapted to support axially an ear of 55 corn, and means for effecting an intermittent partial rotation of the ear, combined with a longitudinally-moving knife, a gaging-roller, and devices for adjusting the position of the said roller with reference to the said knife, substantially as and for the purpose specified.

5. The shaft *B*, having a driving blade or center, and the sliding bar *D*, combined with the longitudinally-moving rod *h*, the same having at one end an eye which surrounds the 65 said driving-blade, and at the other means for effecting an engagement with the said bar *D* or its attachments as the same are retracted from the driving-center, substantially as and for the purpose specified.

SOLOMAN D. WARFIELD.
